UNITED STATES PATENT OFFICE

LIONEL VALLAS, OF CHICAGO, ILLINOIS

ROOF FLASHING

Application filed September 3, 1931. Serial No. 560,944.

My invention relates to flashings for roofs on buildings at the juncture with parapet walls and chimneys; and has for its object the provision of a flashing adapted to be secured in a crevice or joint in the wall or chimney, and arranged to provide a water-proof relation with the roof proper.

Another object of the invention is to provide a flashing which will not be too expensive in manufacture, while at the same time being reenforced at the point where it is apt to become broken or ruptured and where it is subject to wear.

Another object of the invention is to provide a reenforcing element whereby the various flashing sheets are firmly clamped together and said reenforcing clamping element formed so as to provide a shoulder on the upper face of the element adapted to prevent seepage of water to the rear edge of said element and hence to the rear side of the flashing.

Another object of the invention is the provision of a metallic wedge member of pre-arranged construction adapted for insertion in the crevice or joint in the wall or chimney whereby the flashing is firmly held in place; the wedge member being adapted to cooperate with the shoulder for effecting a binding relation between the flashing and the wall or chimney.

The objects and advantages of my invention will be readily comprehended from the detailed description of the accompanying drawing, wherein:

Figure 1 is a sectional elevation of a portion of a roof and a wall, with my improved flashing in place.

Figure 2 is a perspective view of a portion of the upper end of my improved flashing and wedge element in position.

Figure 3 is a sectional view of a portion of my flashing applied to a concrete wall.

As is well known, the weakest point in a roof is at an up-turned angle, namely at the juncture between the roof proper and a chimney or at the juncture with a parapet wall or coping. A majority of leaks occur at such places, due to improper construction of the flashing which prevents proper lap-

ping relation with the roofing material; also because of improper protection or reenforcement of the flashing at the point of its insertion in the wall or chimney crevice; and because of the fact that the inserted portion of the flashing is not made to prevent ingress or seepage of water to the rear side thereof.

At the same time, difficulty has been encountered with the means heretofore employed for securing the flashing in the wall or chimney crevice.

I am aware that flashings have been employed which have been provided with reinforcing plates folded back upon themselves without, however, enfolding the pliable flashing material therebetween so as to firmly clamp the reinforcing plates thereto; such flashings, however, providing no means for firmly wedging or holding the flashing in place aside from the subsequently inserted mortar.

I am also aware that certain flashings have been devised consisting of a plastic material with reinforcing plates embedded therein and wire clips formed which are adapted to have one end press through the plastic outer surface into engagement with the embedded reinforcing plate; a construction which causes the flashing material to be torn when the clips are forced into the wall crevice.

My invention is adapted to obviate the objections heretofore encountered and consists in employing a number of strips or sheets of saturated canvas 5, 6 and 7, impregnated with a suitable water-proofing material; the various sheets being preferably of different and predetermined lengths in order that their interlapping points with the roofing material proper 8 may be disposed at different places on the main roof portion, as shown in Figure 1.

The material or sheets 8, which constitute the main part of the roof, are preferably bent upwardly against the side of the chimney or parapet wall indicated at 9 and disposed between the lower sheet 7 and the intermediate sheet 6 of the flashing, with the intermediate sheet extending on to the main portion of the roof and sealed thereto with suitable material and terminating approximately at the point 100

10; while the outer flashing sheet 5 extends approximately to the point 11 and is sealed to the roof proper. On the other hand, the lower flashing sheet 7 preferably extends 5 beyond the last mentioned point and beneath the main roof material approximately to the point 12; it being understood, of course, that all of the flashing sheets and the main roofing material are sealed together with a suitable 10 water resisting material.

The flashing sheets 5, 6 and 7, before application, have their upper longitudinal edges provided with a metallic reenforcing and protecting strip 13, preferably of aluminum 15 of suitable gauge. This metallic strip extends throughout the upper longitudinal edges of the flashing sheets 5, 6 and 7 and is bent longitudinally with the flashing sheets therebetween so as to provide the bottom leg 20 or portion 14 and the upper leg or portion 15; the two portions being in turn bent downwardly to provide the vertically disposed flange portions 16 and 17, which protect the bent portions of the flashing sheets 5, 6 and 7 25 at the wear encountering points, namely from the breakage or cutting by the edges of the bricks or concrete from which the wall or chimney is constructed; and from the weather and moisture at the upper side of the bent 30 part of the flashing.

After the metal strip 13 has been folded about the flashing sheets 5, 6 and 7, the bent longitudinal side of the metal strip, with the enfolded flashing sheets, is then bent or 35 curled upwardly onto itself by suitable machinery, to provide the shoulder 18, thereby firmly binding the metallic strip to the upper longitudinal edges of the flashing sheets; the enfolded shoulder portion causing 40 the strip to be firmly bound onto the flashing sheets.

Where the flashing is to be employed against a brick wall or chimney, the mortar between certain courses of bricks at a proper 45 distance above the roof, is removed or raked out, as shown in Figure 1, sufficiently to receive the reinforced upper longitudinal end of the flashing; the flashing being inserted into the rattle or crevice so as to have the 50 lower flange portion 16 of the reenforcing strip flush with the side of the wall or chimney as shown.

In order to firmly hold and lock the flashing in place, I provide the metal wedge members 55 19; a suitable number of these wedge members being employed at spaced apart points throughout the width of the flashing. These wedge members are preferably made from spring steel sheets of comparative 60 width, as shown in Figure 2, bent into V-shape so as to provide the two diverging sides 20 and 21 normally spaced apart at the free ends somewhat greater than the vertical dimensions of the rattle or crevice in 65 the wall or chimney.

The side 21 is preferably of somewhat greater width than the side 20 of the wedge member 19, and this side 21 has its free longitudinal edge bent slightly upward, as shown at 22; both longitudinal sides having 70 comparatively sharp longitudinal edges as shown.

After the flashing has been properly inserted into the crevice, the wedge member 19 is then driven into place with a suitable 75 tool inserted into the apex of the member. The free end of the lower side 20 engages the shoulder 18 of the flashing reenforcing strip 13, and the wedge member 19 at its inner bent edge is caused to tilt upwardly 80 and ride over the shoulder 18 in the manner shown in the drawing, which in turn induces the edge of the lower side 20 to somewhat indent itself in the metal reenforcing strip 13, while the upturned portion 22 of the upper side 21 will embed or force itself 85 into the brick above the crevice. It is apparent that the wedge member will thus firmly hold the flashing in position. The crevice may then again be filled with cement or mortar or any other suitable binding material. 90

In Figure 3, I illustrate application of my improved flashing to a cement or concrete wall 23 which, at a proper distance above the roof proper, has been provided with a 95 crevice or rattle 24 for the reception of my flashing, which is similar to the flashing shown in Figures 1 and 2 as heretofore described.

With the flashing provided with the metal 100 binding constructed and arranged as shown and herein described, the sheets of flashing fabric are fully protected at the bend where reenforcement and protection are very essential and resistance to the action of rain and 105 snow afforded.

Furthermore, by bending the inner longitudinal edge of the flashing and reenforcing strip into the upstanding shoulder 18, the 110 passage of water, which may seep through the remortared crevice, to the rear side of the flashing, will be prevented; while at the same time this shoulder 18 acts as a stop for the wedge member which rides into the crevice in the tilted manner shown, thus permitting 115 its inner edge to ride over the shoulder while the forward lower longitudinal sharp edge is in gripping relation with the flashing reenforcing strip forward of the enfolded or curled portion. 120

The rattle or crevice 24, like that in the brick wall or chimney, after the flashing has been inserted into place as shown is, of course, filled in with concrete, mortar or other suitable material; and although the juncture between the mortar, or cement and the reenforcing strip may not be absolutely moisture proof, any seepage of water therethrough will be prevented from passage to the rear of the flashing by the shoulder 18. 125 130

As shown in the drawing, the wedge members are formed of sheets of resilient metal of comparative length; the sheets being bent into V-shape and preferably with one leg or side of somewhat greater width than the other and this wider side adjacent to its longitudinal edge bent outwardly or upwardly as shown. By having the bent side somewhat wider, the wedge member when inserted into the crevice is caused to tilt upwardly as shown, the upwardly bent portion constituting a fulcrum point, which therefore induces the apex portion of the wedge member to also engage with the wall at the top of the crevice, thereby providing three gripping portions to the wedge member, with each gripping or contact portion disposed in a different vertical plane, as it were, which prevents any possibility of lateral movement of the wedge member. At the same time the sharp longitudinal edges of the two legs or sides of the wedge member are brought into gripping or binding position, which, in practice, has been found makes shifting or accidental displacement of the wedge members impossible; while the position of the wedge members relative to the flashing proper is determined by the shoulder on the upper side of the inserted portion of the flashing.

In practice preferably a number of wedge members are employed for each flashing unit; but with the rigid binding along the upper edge of the flashing it is apparent that the full length of the flashing will be held in place if only a single wedge member was employed.

I have shown what I believe to be the best embodiment of my invention and have described the same in terms employed merely as terms of description and not as terms of limitation as structural modifications may be made without, however, departing from the spirit of my invention.

What I claim is:

1. Flashing of the character described comprising a plurality of saturated sheets of fabric; a sheet metal reenforcing strip for the upper longitudinal edges of the fabric sheets, bent along a longitudinal line with the edges of the fabric disposed at said bend, the two parallel sides of said metal strip with the enfolded fabric sheets then bent upwardly to provide a shoulder along the upper longitudinal edge of the flashing; and a resilient wedge member adapted to ride onto said shoulder into tilting position with one longitudinal edge in bearing relation with the upper side of the metal reenforcing strip while the other longitudinal edge is in binding relation with the upper side of a crevice in the wall to which the flashing is applied.

2. A flashing of the character described comprising a plurality of sheets of fabric adapted to receive composition roofing material therebetween, a reenforcement for the

upper ends of the flashing fabric consisting of sheet metal folded about the upper edges of the fabric, the sheet metal, with the enfolded fabric, at the folded edge being bent upwardly and onto the upper face of the flashing to provide a shoulder; and wedge members of resilient sheet metal to be disposed on top of the reenforced end with one longitudinal edge in engagement with said shoulder while the other longitudinal edge is bent upwardly to engage the upper side of a crevice in the wall to which the flashing is applied.

3. In a flashing composed of fabric, a metal binding for the upper longitudinal edge thereof composed of a sheet of metal folded back upon itself with the fabric therebetween and the bent longitudinal side with the fabric then bent back upon the upper side to provide a shoulder on the upper side of the flashing; and a V-shaped wedge member of resilient metal adapted to be forced into a wall crevice on top of said binding strip with the apex of the wedge member disposed horizontally while the upper side of the wedge member is bent upwardly to form gripping relation with the wall at the upper side of the crevice.

4. In a roof flashing, the combination of flashing material adapted to have the upper end inserted in a wall crevice above the roof, while the other end is arranged in lapping relation with the roof proper, said upper end on its upper side being provided with a shoulder; with a V-shaped wedge member of resilient material adapted to be forced into the wall crevice on top of the flashing material with one side of the wedge member against said shoulder while the other side is in engagement with the wall of the upper side of the crevice.

5. In a roof flashing, the combination of pliable flashing material, the upper end whereof is provided with a metallic binding strip of width greater than the extent of insertion of the flashing in the crevice of a side wall, said binding strip at its inner longitudinal edge being provided on its upper surface with a shoulder; with a wedge member formed from a sheet of resilient metal bent into V-shape and adapted to be forced into the wall crevice on top of said binding strip, with one side in engagement with said shoulder while the other side is in engagement with the wall at the upper side of the crevice.

6. In a roof flashing of the character described, the combination of a plurality of sheets of pliable material, the upper ends whereof are provided with a metal strip folded thereabout and the folded edge of the strip with the ends of the material bent upwardly to provide a shoulder; with a wedge member of resilient sheet metal bent into V-shape adapted to be forced into a wall crevice on

top of the metal strip with the apex of the wedge member disposed inwardly, with one side of the wedge member arranged in engagement with the metal strip while the other side is in engagement with the wall at the upper side of the crevice.

- 5 7. In a roof flashing, the combination of flashing material adapted to have the upper end inserted in a wall crevice, the upper surface of the flashing adjacent the inserted longitudinal edge being provided with an upwardly disposed portion; with a wedge member composed of an elongated strip of stiff sheet metal bent longitudinally into V-shape and the upper longitudinal side curled upwardly, with the apex of the wedge disposed inwardly over the upwardly disposed portion of the flashing so as to cause said wedge member to tilt upwardly and force 10 one longitudinal edge of each side of the member into gripping relation with the flashing and with the upper wall of the crevice.
